UNITED STATES PATENT OFFICE.

GEORGES GUSTAVE URBAIN MARIE MAIRESSE, OF PARIS, FRANCE.

COLOR-PRINTING PROCESS.

Application filed March 19, 1924. Serial No. 700,326.

To all whom it may concern:

Be it known that I, GEORGES GUSTAVE URBAIN MARIE MAIRESSE, a citizen of the French Republic, residing at Paris, France, have invented new and useful Improvements in Color-Printing Processes, of which the following is a specification.

The present invention relates to a process for printing in color upon textiles, leathers or other appropriate materials or supports, by embossing, stamping or goffering.

This process consists essentially in this that between the textile fabric or other support to be printed and the stamping, embossing or goffering roller raised to a sufficient temperature (about 50° to 60° C.), there is interposed a carrier-sheet of paper or other suitable support previously coated with a thin layer of paraffin wax, stearine or other appropriate fatty body mixed with suitable color, this layer being placed against the textile or other support.

By reason of this process, under the action of the stamping, embossing or goffering, the textile or other support is imprinted more or less in intaglio according to its thickness, at the places subjected to the pressure of the parts in relief on the stamping or embossing roller, by reason of the melting of the fatty body, which yields or gives up solely at these places and in contact with the hot metal of the plate or roller, the color which it contains.

A further improvement consists in interposing between the textile or other support to be printed upon, and the color-bearing layer of paraffin or other fatty body, a suitable very loose textile fabric preferably with openwork or holes such as tulle, bolting-cloth, canvas, of any suitable coarseness.

At the time of the melting of the fatty body, the threads of this interposed loose textile absorb the liberated color pressed upon them, thereby shielding or saving that part of the textile or material to be printed, which is placed below them. This interposition thus enables to be reproduced in the design printed upon the support or material and in the tone or shade even of this support, the particular design of the interposed textile, which arrangement gives generally a lighter appearance to the general design; on the other hand, this same operation causes at the same time the impression of the tulle, bolting-cloth or other textile interposed.

A secondary process derived from the principal process consists in utilizing the paper or other support coated with a colored fatty body, which have once already served and consequently have lost their facility for printing in the lines of the original design, for the purpose of printing by pressure between two smooth-surfaced rollers upon a textile or other printing support, a general colored background upon which the original design thus stands out by contrast in the normal tone of this support as a negative of the shielded original.

The interposition of the paper or other support coated with a colored fatty body between the textile or other support to be imprinted and the embossing or goffering roller, can be effected in any manner whatever.

The annexed drawing shows diagrammatically and by way of example, a mechanical arrangement enabling this process to be utilized.

In these drawings *a* represents the heated roller engraved in relief, and *b* the smooth-surfaced roller forming the pressure cylinder. The textile *c* to be printed, wound upon the roller *d* is subsequently, after printing, wound upon the roller *e*. The carrier-sheet coated with a fatty body which may be paraffin-waxed paper *f*, is wound upon the roller *g* and guided by the rollers *h* and *h'*; after use it is wound upon the roller *i*. The roller *a* is heated by any suitable means.

The process can be applied to existing stamping machines by arranging the roller which carries the paraffined paper upon two arms adapted to be secured to the machine.

Having thus described my invention, what I claim is:—

1. Process for color-printing textiles, which consists in passing the textile between rollers, one of said rollers being engraved and the other smooth-surfaced, heating said engraved roller, interposing between the material and the engraved roller a carrier-sheet coated on one side with a color-bearing fatty body, melting the colored fatty body at the raised parts of the engraved roller by means of the heat from the roller, and arranging a sheet of loose fabric between the material to be color-printed and the said carrier-sheet coated on one side with a colored fatty body.

2. Process for color-printing textiles, which comprises passing the textile between an engraved roller and a smooth-surfaced roller, heating said engraved roller, interposing between the textile and the engraved roller a carrier-sheet coated on one side with a color-bearing fatty body, and insert-
ing between the carrier-sheet and the textile a sheet of openwork material to shield the textile in part from the color-bearing fatty body.
- 5 In testimony whereof I have signed my name to this specification.

GEORGES GUSTAVE URBAIN MARIE MAIRESSÉ.
